Howson & Howson

UNITED STATES PATENT OFFICE.

FRANK CRAWFORD, SR., OF NEW BRUNSWICK, NEW JERSEY, ASSIGNOR TO CRAWFORD MANUFACTURING COMPANY, OF NEW BRUNSWICK, NEW JERSEY, A CORPORATION OF NEW JERSEY.

TRIP MECHANISM FOR KNITTING-MACHINE STOP MOTIONS.

Application filed February 18, 1926. Serial No. 89,136.

This invention relates to trip mechanism for knitting machine stop motions, and more particularly to that class of knitting machine on which circular knit hosiery is produced. 5
5 In a knitting machine of this type, when the heel and toe portions of the stocking are being knit, it is desirable to have the thread running free through the thread guides and under little or no tension. 10
10 In accordance with the principles of my invention, the only tension on the thread is that applied by the drop wire of the stop motion. The drop wire, in this particular instance, is constructed of comparatively fine 15 gage steel wire of inconsequential weight.

The principal object of my invention is to provide a trip arm for the stop motion of a knitting machine which shall be of sufficient weight to efficiently operate the stop motion, 20 under the control of the drop wire of the stop motion and at the same time reduce the tension applied to the knitting thread, by the drop wire, to a minimum.

In the accompanying drawings: 25
25 Fig. 1 is a perspective view of my invention with one of the cover plates removed.

Fig. 2 is a face view, with the front cover removed.

Fig. 3 is a rear view, partly in section, 30 with the rear cover removed.

Fig. 4 is a perspective view of the drop wire and its associated pivot element.

Fig. 5 is a perspective view of the stop motion trip arm.

35 Fig. 6 is a perspective view of the latch controlled by the drop wire.

Fig. 7 is a perspective view of the intermediate lever associated with the drop arm shown in Fig. 5.

40 As shown in Fig. 1 of the drawing, 1 is a thread guide arm, forming part of a stop motion of a knitting machine, and provided with a supporting plate 2 positioned at right angles and extending vertically from the

45 arm 1. The plate 2 is provided with a forwardly extending horizontally disposed bracket 3 having a reduced vertically extending arm 4 which is provided with a wing 5 extending rearwardly and parallel to the bracket 3. In the bracket 3 and the wing 5, I provide the usual porcelain thread eyes 6 and 7 respectively.

50 Between the thread eyes 6 and 7, I posi-

tion a hooked portion 9 of a drop wire 8, 55 said drop wire being provided with a pivot element 10 journaled in a bearing 11 formed on the plate 2. The pivot element 10 is provided with a downwardly projecting arm 12 adapted to engage the lower end of a latch member 13 which is pivoted at 14 to a 60 bracket 15 secured to the plate 2.

The latch member 13 is provided with a shoulder 16 adapted to be engaged by a projection 17 on an intermediate lever 18 which is pivoted at 19 to the bracket 15. The intermediate lever 18 is provided with a slot 20 into which projects a pin 21, secured in a weight 22 on the outer end of a trip arm 23. The trip arm 23 is secured to the outer end 65 of a trip rod or shaft 24 which is journaled in bearings 25 formed in the arm 1, and is adapted to trip the stop motion of the knitting machine (not shown).

As shown in the drawings, the intermediate lever 18 is pivoted adjacent one face of the plate 2, and the weight 22 occupies a position adjacent the opposite face of the plate 2, a slot 26 being provided in the plate 2 for the accommodation of the pin 21, when the arm 23 moves about the pivotal center of 70 the shaft 24.

In operation, and as shown in Fig. 1, a thread X passes through the eyes 6 and 7, and is engaged, intermediate the two said eyes, by the hook portion 9 of the drop wire 8. The arm 23 is supported in its inoperative position, shown in Figs. 2 and 3, by means of the projection 17 of the arm 18 being engaged by the shoulder 16 of the latch member 13. The arm 12 of the drop wire 8 is adapted to lie in contact with the lower portion of the latch arm 13.

Under normal operating conditions, the thread X passes through the eyes 6 and 7 under very slight tension. The thread is lightly engaged by the hook member 9, and the drop wire 8 is thereby held in an inoperative vertical position and being of comparatively fine wire and of very little weight little or no tension is applied to the thread by the drop wire.

Should the thread X become broken, the drop wire 8 is immediately released. Its body portion lying to one side of its pivotal center causes the drop wire 8 to turn its pivot element 10 thereby causing the arm 12

thereof to engage and move the latch member 13 on its pivot 14.

The movement of the latch member 13 causes the shoulder 16 thereof to release the 5 projection 17 of the arm 18, permitting said arm to move about its pivotal center 19. The movement of the arm 18, through the slot 20 and pin 21, permits the weight 22 to fall, moving in a path concentric with the 10 center of the shaft 24, which is turned thereby. The turning of the shaft 24 trips the stop motion (not shown) causing the knitting machine to which it is attached to be stopped.

15 From the above description, it will be apparent that I provide a thread guide and tripping mechanism for a stop motion in which little or no tension is applied to the knitting thread passing therethrough. 20 However, should the thread break, the mechanism is released and the knitting machine stopped immediately.

To prevent the yarn fly and other dust from accumulating on the elements forming 25 my invention I provide flanged cover plates 30 and 31 which are secured to the front and rear faces respectively of the supporting plate 2, in any suitable manner. The front cover plate 30 is apertured at 32 and 33 for 30 the free movement of the drop wire 8 and the trip arm 23 respectively.

35 While I have shown but one preferred embodiment of my invention, it will be apparent that numerous modifications to the mechanism are possible without departing from the essential features of my invention, therefore, the illustration is not to be construed as limiting the invention to the precise construction shown, and I desire that only such limitations be placed thereon as may be prescribed by the appended claims or necessitated by the prior art of record.

40 What I claim is:

1. In trip mechanism for knitting machine stop motions, the combination of a pivoted weighted arm adapted to trip said stop motion; a pivoted drop wire of inconsequential weight supported by the knitting thread running in the knitting machine; a 45 projection on said weighted trip arm; a pivoted intermediate lever engaging said projection; a latch engaging said intermediate lever; and a projection on said drop wire adapted to engage said latch and thereby 50 release said trip arm when said drop wire is permitted to rotate as by breakage of said thread.

2. In trip mechanism for knitting machine stop motions, the combination of a supporting element; a weighted trip arm pivoted on said support; a drop wire pivoted on said support and adapted to be held in an inoperative position by a knitting thread running in the knitting machine; an intermediate lever pivoted on said support; a pro-

jection on said weighted trip arm normally occupying a position immediately adjacent the pivot of and engaged by said intermediate lever; a latch pivoted on said support and normally engaging the free end of said intermediate lever; and an arm projecting from the pivot element of said drop wire adapted to engage and release said latch whereby said trip arm is released when the said drop wire is permitted to rotate as by 75 breakage of said thread.

3. In trip mechanism for knitting machine stop motions, the combination of a supporting element; a weighted trip arm pivoted on said support; a drop wire pivoted on said support and adapted to be held in an inoperative position by a knitting thread running in the knitting machine; a longitudinally slotted intermediate lever pivoted on said support; a projection on said weighted trip arm normally occupying a position immediately adjacent the pivot of said intermediate lever and extending into the slot thereof; a latch normally engaging the free end of said intermediate lever; and an arm projecting from the pivot element of said drop wire adapted to engage and release said latch whereby said trip arm is released when the said drop wire is permitted to rotate as by breakage of said thread.

4. In trip mechanism for knitting machine stop motions, the combination of a supporting arm; a supporting plate secured to said arm; a stop motion trip rod journaled in said arm; a weighted trip arm secured to said rod; a drop wire pivoted to said supporting plate; a latch pivoted to said supporting plate; an intermediate lever pivoted to said supporting plate and adapted to be engaged by said latch; a slot in said supporting plate; a pin on said weighted trip arm, passing through said slot and co-operatively engaging said intermediate lever, and an operating arm on the drop wire pivot element for engaging the latch, for subsequent actuation of the said elements when the knitting thread of said machine breaks.

5. In trip mechanism for knitting machine stop motions, the combination of a supporting arm; a supporting plate secured thereto; a bracket secured to said supporting plate; a wing on said bracket; a thread eye in said bracket; a thread eye in said wing aligned with the thread eye in said bracket; a drop wire pivoted to said supporting plate and extending into a position intermediate said thread eyes, for engagement with a thread passing therethrough; a weighted trip arm pivoted to said supporting arm and adapted to be controlled by said drop wire; and said means intermediate said drop wire and said weighted trip arm, operable by said drop wire, for effecting the actuation of said trip arm.
